United States Patent Office.

SYLVANUS SAWYER, OF FITCHBURG, MASSACHUSETTS.

Letters Patent No. 78,238, dated May 26, 1868.

IMPROVEMENT IN RATTAN-MACHINES.

The Schedule referred to in these Letters Patent and making part of the same.

TO ALL WHOM IT MAY CONCERN:

Be it known that I, SYLVANUS SAWYER, of Fitchburg, in the county of Worcester, and State of Massachusetts, have invented certain new and useful Improvements in Machines for Splitting Sticks of Rattan into Strands or Sections; and I do hereby declare that the following is a full, clear, and exact description of the same, taken in connection with the accompanying drawings, making part of this specification, in which—

Figure 1 is a plan of the machine, with a part in horizontal section.

Figure 2 is a side elevation.

Figure 3 is a transverse section on the red line of figs. 1 and 2.

The other figures represent various details and modifications of the machine, which will be referred to in the description.

The subject-matter of my invention relates to the construction of an apparatus for splitting sticks of rattan into strands or segments for chair-cane, so called, and for other purposes, or for splitting any other material for which the machine may be adapted; and consists, in the first place, in the use of a series of revolving disk-cutters, which have their planes of revolution parallel to the axis of the stick to be split, and arranged radially around the stick, at such angular distances apart as will separate the circumference of the stick into the required number of parts, as the stick is passed between them, in combination with a series of adjustable guides so constructed that the said guides shall adapt themselves to the varying size of the stick, and so arranged in relation to the said splitters as to present the stick centrally to them as it is carried forward to be split; and it consists, in the second place, in so connecting each revolving cutter and its guide with the other cutters and guides of the series, that they shall be made to simultaneously approach and recede from the centre of the stick, so as to keep it in a central position while the said cutters and guides can adapt themselves to the varying size of the stick; and it consists, in the third place, in combining, with a series of revolving splitting-cutters and self-adjusting guides, an annular cutter, so arranged that the said guides shall present the stick centrally both to the said annular cutter and splitting-cutters, as will be described; and it consists, in the fourth place, in the employment, in combination with a splitting-apparatus, substantially such as is before mentioned, of a suitable feeding-apparatus, consisting of feeding-rollers, or other equivalent means, by which the stick will be carried forward to the cutters to be operated upon by them.

In the drawings, A represents the frame of the machine, upon which the operative parts are arranged, as shown. B is the driving-shaft, to which the power is applied to operate the machine. C is a vertical shaft, gearing with the shaft B, which, by means of the gear C', distributes the power to two series of feed-rollers, D D¹ and E E¹, arranged in pairs on vertical shafts, between which the stick is seized, and carried forward through the machine.

The proper motion of these feed-rollers is secured by means of the gears D² and E², upon the lower ends of these shafts, and the intermediate gears F, which transmit the power from one pair to another. The several pairs of rollers have their peripheries hollowed to receive the stick, and they are forced towards each other, to gripe the stick, by means of rubber cushions, or other suitable springs, placed behind the upper bearings of their shafts.

Between the two series of feed-rollers D D¹ and E E¹ is placed the cutter-stock G, in which the revolving splitting-cutters H are arranged as shown, by which the circumference of the stick is divided into strands. The cutters H may be used in any required number, according to the size of the stick operated upon, and the width to be given to the strand. Each of the cutters is mounted in a slide, I, which is fitted to move radially in the stock G, and the several slides are connected by the gears I', working on studs, fixed in the stock, so that they simultaneously approach and recede from the centre of the stock to accommodate the varying size of the stick as it passes through. The construction of the cutter H and guide h are seen most clearly in Figures 4 and 5.

The slides are forced towards the centre by the leaf-springs J, each one of which operates two of the slides,

as shown, and its pressure is tempered by the screw *j*. The motion of the slides toward the centre is limited by adjustable stops, *i*, at the outer ends of the slides.

Upon either side of the cutters *H* are placed the guide-rollers *h*, which bear upon the surfaces of the stick, and keep it central between the cutters. *K* is a tubular or annular cutter, which is held in the cutter-stock *L*, as is seen in Figures 6 and 7, and is placed with its axis in line with the centre of the stock *G*, and the recesses of the feed-rolls, and has an aperture throughout its length, through which the pith or central portion of the stick passes, while the exterior of the stick, which has been previously divided by the revolving cutters, passes off outside of the cutter *K*, in the form of separate strands.

The central portion of the stick after leaving the cutter *K* passes between the feed-rollers *E E'*, which thus assists in forcing the stick through the machine. The strands are directed upward above the last series of feed-rollers by the chute *L*, which gathers them after they are split off. *M* is a guide, through which the stick passes to the feed-rollers *D D'*.

In operating this machine, the stick of rattan is inserted through the guide *M*, between the feed-rollers *D D'*, which, carry it forward to the revolving cutters, which, rolling along its surface, make a series of longitudinal incisions therein; the position of the stick being maintained by the guide-rollers *h*, which rest upon its surface, upon either side of the cutter *H*. By the simultaneous movement of these roller toward and from the centre, by means of the construction described, and by their yielding pressure, they serve to hold the stick centrally and firmly to the cutters, notwithstanding its varieties of size.

After the stick has passed the splitting-cutters, it meets the tubular cutter, which splits off the entire exterior of the stick, divided into strands by the incisions of the splitting-cutters, while the central portion of the stick passes through the tubular cutter, and between the several pairs of feeding-rolls *E E'*, which assist in carrying the stick forward. The several strands are, by means of the chute *L*, led above the feed-rolls *E E'*, and discharge, ready for subsequent operations.

This splitting-apparatus is capable of a variety of modifications in its construction, while retaining its substantial character and mode of operation; as, for instance, instead of forming the guides for directing and holding the stick by the rollers *h*, upon the sides of the cutters *H*, guiding-surfaces may be attached to the several slides *I*, upon either side of the cutter, which projects the required distance beyond them, as is shown in Figures 9 and 10, or separate self-adjusting guides may be placed in front of the series of splitting-cutters, as is shown in Figure 8, instead of attaching them to the slides *I*, in which case the splitting-cutters, after being approximately adjusted to the size of the stick, may be held stationary. And so of the feeding-mechanism, other devices may be used instead of the feeding-rollers, to carry the stick forward, as, for instance, the employment of a pair of endless-apron chains, between which the stick is held, and other modifications of mechanism may obviously be used to embody the same mode of operation. And such a splitting-apparatus may obviously be employed to split other kinds of material and larger sticks than rattan.

What I claim as my invention, and desire to secure by Letters Patent, is—

1. The combination of the series of revolving splitting-cutters with the series of guides, substantially as described.
2. Combining each revolving cutter and its guide with the other cutters and guides of the series, by means of the gears *I*, so that they shall be made to simultaneously approach and recede from the centre of the stick, substantially in the manner and for the purpose described.
3. The combination of the series of revolving splitting-cutters with the annular or tubular cutter, substantially as described.
4. The combination of the revolving splitting-cutters, the tubular cutter, and the guides, substantially as described.
5. The combination of the splitting-apparatus, before described, with a suitable feeding-mechanism for carrying forward the stick, substantially as described.

Executed at Boston, this 25th day of February, 1868.

SYLVANUS SAWYER.
